YARN CARRIER CONTROL MECHANISM FOR
STRAIGHT OR FULL-FASHIONED KNIT-
TING MACHINESPaul Schmidt, Wyomissing, Pa., assignor to Tex-
tile Machine Works, Wyomissing, Pa., a cor-
poration of Pennsylvania

Application May 21, 1935, Serial No. 22,536

17 Claims. (Cl. 66—127)

My invention relates to means for selectively maintaining the carrier rods of a flat knitting machine inoperative during the operation of actuating means therefor, and particularly to means for automatically selecting the rods for such operation in accordance with the pattern of a fabric being knitted.

During the production of hosiery on a full fashioned knitting machine, it is necessary to periodically substitute one yarn for another, as when a ravel course is formed, or to supplement one yarn by another, as during a plating operation.

Since it frequently becomes necessary to move the couloring mechanism through inoperative cycles, as when certain carriers are held stationary, while others are repositioned at different points in the knitting field, and while all of the carriers are connected to their actuator mechanism, means must be provided for repositioning the couloring mechanism to effect this action. These inoperative movements of the couloring mechanism are known as "idle courses".

It is among the objects of this invention to provide novel means in a knitting machine for automatically locking reciprocal elements, as above indicated, against the action of the operating members thereof, preferably as effected through frictional engagement with the actuating means, and to selectively hold, and release, the elements, particularly as related to the selection, and positioning, of yarn carriers for effecting idle courses.

Another object is to provide, in a knitting machine, novel pattern-controlled means operable to selectively prevent, and provide for, movement of reciprocal yarn carrier rod elements in predetermined order, and particularly to means for selectively controlling the movements of frictionally reciprocated rod elements relative to movements of the actuating mechanism, without disconnecting intermediate frictional connectors, thereof.

A further object is to provide novel means, including a central control shaft, whereby yarn carrier rods may selectively be held inactive during reciprocatory movements of the driving mechanism thereof, without disconnecting an intermediate driving means.

It has heretofore been suggested to control an auxiliary pattern unit by a main pattern chain or device, of a knitting machine, by a mechanism including a constantly operating power-supplying element for operating the auxiliary unit, as selected for operation by the main pattern device. In other words, the connection or linkage, between the auxiliary and main pattern units, in-

cludes a member, which, although moving constantly, is ineffective, except as periodically rendered effective in accordance with the pattern. Thus, undue vibration, wear and other undesirable features are presented.

According to my invention, the above disadvantage is avoided, and a device provided, in which none of the parts operates idly, or until required to operate according to the pattern.

With these and other objects in view, which will become apparent from the following detailed description of the illustrative embodiment of the invention shown in the accompanying drawings, my invention resides in the novel mechanism and means for operating the same, as hereinafter more particularly pointed out in the claims.

In the drawings:

Figure 1 is a plan view of a portion of a full-fashioned knitting machine embodying my invention;

Fig. 2 is a cross-sectional view of a portion of a full-fashioned knitting machine, illustrating the invention with respect thereto;

Fig. 3 is a view, taken substantially along the line 3—3 of Fig. 1, showing control and carrier rod locking mechanism thereof;

Fig. 4 is a view, similar to Fig. 3, showing elements for locking certain of the carrier rods;

Figs. 5, 6, and 7 illustrate the locking mechanism for other carrier rods;

Fig. 8 is a detail view, in section, of a means employed to lock certain of the yarn carrier rods;

Fig. 9 is a diagram of the leg blank of a full-fashioned stocking, together with a plurality of pattern chains, as developed or opened out along straight lines in side elevation, from the normally looped shape, indicating the positions along the blank at which the lock levers are operated and the corresponding links of the chains by which such operations are effected;

Fig. 10 is an enlarged view of the bottom part of the blank of Fig. 9;

Figs. 11 to 22, inclusive, are diagrams of the carrier rods and lock levers, in sequence positions during the knitting operation;

Figs. 11a to 22a, inclusive, are end views, with adjacent end stops omitted, of the structures of Figs. 11 to 22, respectively; and

Figs. 11b to 22b, inclusive, are similar views of the opposite ends of the structures of Figs. 11 to 22, inclusive.

Figs. 1 to 3 illustrate various parts of a Read-
ing full fashioned knitting machine embodying the mechanism and elements of my invention.

For clearness, only those parts of the various mechanisms necessary for an understanding of the invention are shown; the other parts, and the operation thereof being well known in the art, as shown and described in the "Reading" Full Fashioned Knitting Machine Catalogue, copyright 1929, and published by the Textile Machine Works, Reading, Pennsylvania.

Referring to the drawings, a cam shaft 10, which supports cams for imparting movement to various units of the machine, is rotatably journaled in bearings that are disposed on end and center frames 12 and 13, respectively, which are maintained in spaced relation by transverse tie members, including a front beam 14, a back beam 15, a front bed 16 and a center bed 17. This structure forms a base upon which the knitting mechanism proper is disposed.

Through means of axially shiftable cams 18 and 19, and a cooperating chain-motion mechanism M, or main pattern device, the cam shaft 10 may readily be shifted from its normal position to the right, as viewed from the front of the machine. In the latter position of the shafts, 25 the narrowing heads N are operated, while the individual mechanisms are operated through narrowing cycles by corresponding narrowing cams on the shaft 10.

The yarn carriers 9, mounted on the reciprocable carrier rods 1 to 8, respectively, are operated by friction boxes 20, one of which is shown in Fig. 2, which are frictionally connected to a friction rod 22, to feed the respective yarns thereof to needles 23, Fig. 2; the needles 23 being clamped to the needle bar 24, which is actuated by the needle and presser levers 25 and 26. The levers 25 and 26 are operated by cams on the cam shaft 10. Sinkers 27 and dividers 28 cooperate with the needles 23 to form loops.

40 The forward movement of the sinkers is effected by a reciprocable cock box assembly 29, through means of intermediate jacks 30. The forward movement of the dividers 28, and the retracted movement of the sinkers 27 and the dividers 28, are effected by a catch bar 32, the movement of which is effected by cams on the cam shaft 10. This movement is transmitted to the catch bar 32 through linkage including a cam follower 33, a cam lever 34, a horizontal catch bar shifter 36, and a vertical shifter arm 35.

An auxiliary pattern unit includes a control shaft 37, Fig. 3, supported by bearing members 38 attached to a transversely extending bar 39, which is secured to the center frames 13 and to the end frames 12. The shaft 37 is intermittently racked by a cam 40, when a lever 42, pivotally mounted on the front beam 14, by a pin 43, is moved counterclockwise, as viewed in Fig. 60 1, by actuation of a rod 44. This movement of the rod 44 is effected by buttons 46 mounted on the auxiliary chain 47, which is operated by, and attached to, the main chain-motion mechanism M.

65 Removal of the lever 42, from beneath the horizontal arm of a bell crank 48, permits a follower 49 to move in accordance with the contour of the cam 40, whereupon rotation of the shaft 37 is caused by the intermittent movement 70 of a ratchet wheel 50 secured thereto. The ratchet wheel 50 is actuated by a pawl 52 that is pivotally mounted on a member 53. The latter is rotatably mounted on the shaft 37, and connected, by a link 54, to the upper end of the bell crank 48.

A spring 55 is anchored, at one end, to the back beam 15, by a bracket 56, and has its opposite end connected to a hook portion of the link 54, thereby providing means for holding the cam follower 49 in yielding engagement with the cam 5 40 when the lever 42 disengages the lever 48, as indicated in Fig. 3. A toothed lever 57, pivotally mounted on a pin 58, is held in yielding engagement with the teeth of the ratchet wheel 50, by a spring 59, to prevent reverse movement 10 of the control shaft, and to permit forward, or clockwise, rotation thereof, as viewed in Fig. 3.

In accordance with the invention, see Figs. 1, 4, 5, 6, and 7, control chains 60, 62, 63, and 64, are, respectively, mounted in sprocket wheels 65, 15 66, 67, and 68, that are separately mounted on the control shaft 37, and rotate in unison therewith. The chains are held in operative position by idler wheels 69, 70, 72, and 73, respectively, which are supported by the back beam 15, as indicated in Fig. 4.

Rollers 74, 75, 76, and 77, for cooperation with the control chains 60, 62, 63, and 64, are rotatably mounted on levers 78, 79, 80, and 82, which are pivotally supported by rods 83 and 84, the latter being secured to the transverse bar 39, by means of brackets 85 and 86.

Foot portions of carrier lock levers 87, 88, 89, and 90, having oscillating and axial movement on supporting shafts 92 and 93, carry rods 87a, 30 88a, 89a, and 90a, which are embraced by forked ends 78a, 79a, 80a, and 82a, of roller supporting levers 78, 79, 80, and 82 thereby providing extensible connections between the respective rods and forked ends providing lost motion longitudinally of the machine between the roller-supporting levers, which are disposed in fixed positions longitudinally of the machine, and the carrier lock levers which are adapted for movement longitudinally of the machine. Rollers 74, 75, 40 76, and 77, supported by the levers 78, 79, 80, and 82, respectively, are held in yielding engagement with their respective control chains, by springs 84, 85, 86, and 87, having corresponding ends connected to the levers 78, 79, 80, and 82, 45 respectively, and the other ends connected to brackets 110, 111, 112, and 113, anchored to the bar 39.

The lock levers 87, 88, 89, and 90 are held in unlocking position, when normally high links 50 of the individual control chains 60, 62, 63, and 64 are in engagement with the corresponding follower members. Locking operation of member 87 is established by engagement of two lock portions or projections thereof with carriers 1 55 and 3, only when the low link 60a engages the follower 74; locking operation of member 88 is established by engagement of three such projections with carriers 4, 6, and 8, only when the low link 62a engages the follower 75; locking 60 operation of member 89 is established by engagement of two lock projections with carriers 5 and 7, only when the low link 63a engages the follower 76, and locking operation of member 90 is established by engagement of one projection 65 with the carrier 2, only when the low link 64a engages the follower 77; the members 87 to 90, inclusive, thereby each embodying a lock portion or portions of different number and location from another for cooperation with a selected 70 number of the rods, and the members 87, 88, and 89 each constituting a single means for selectively locking and substantially simultaneously releasing a plurality of the carriers in accordance with a pattern.

As indicated in Fig. 8, secured to the carrier rod 2, is a stop or dog member 2a, carrying a screw 2c for engaging the corresponding lock lever, and for adjusting the space relation, longitudinally of the carrier rod 2, between the lock levers and the stops. The carrier rods 1, and 3 to 8, inclusive, are similarly provided with stops 1a, and 3a to 8a, inclusive, as indicated diagrammatically in Figs. 11 to 22, inclusive, also having similar adjusting screws, not shown. Thus the lock lever 90, see Figs. 7 and 8, which locks the carrier 2 is lowered into its locking position of Fig. 8, when either of the low links 64a is positioned beneath the roller 71. The action of the spring 97 moves the lever 82 counterclockwise, as viewed in Fig. 7, for imparting a clockwise movement to the lock lever 90, and lowering the free end thereof into locking position relative to the screw members 2c on the carrier 2, to lock said carrier against operation in one direction by the respective actuating unit thereof.

When the low links 60a, 62a, 63a, and 64a, of the control chains 60, 62, 63, and 64, respectively, are beneath the respective rollers 74, 75, 76, and 77, the locking levers 87, 88, 89, and 90 are in lowered operative position relative to the respective carrier rods thereof. This locking action is maintained until a following rotative movement of the control shaft 37 moves the low links from beneath the rollers, and positions high links therebeneath, to again raise the locking levers, so that the carriers are again free to continue their reciprocative travel.

The locking members 87, 88, 89, and 90 are preferably operative during complete cyclic movements of the carriers, and cannot be released during the course of couloring, inasmuch as movements of the chain 47, and consequently, of the control chains 60, 62, 63, and 64, are effected only between couloring operations.

The device is particularly adapted for use in conjunction with the automatic operation of full fashioned knitting machines, while effecting "idle courses", during the fabrication of hosiery; an "idle course" resulting when the machine is operated through a usual knitting cycle, without producing loops, and without pressing the loops, of adjacent previously knitted courses, from the needles. This action is necessary, when the couloring mechanism must be moved across the knitting field, to engage a desired carrier or place it out of operation, the normal inoperative position of which carrier is on the side of the knitting section opposite to the side at which the carrier must be placed into, or taken out of, operation.

The links, of the control chains 60, 62, 63, and 64, determine the sequence of operation of the lock levers 87, 88, 89, and 90, which hold the carriers at certain times, during the knitting of a full-fashioned stocking blank, as indicated in Figs. 9 and 10. The control chains 60, 62, 63, and 64, see Fig. 9, control the action of the carrier lock levers of the machine from a line 115, in advance of the first course knitted in the welt, to a course 116 of the heel tabs T.

The stocking leg blank L extends, from the top edge of the folded welt portion W, to the course 116 of the heel tabs T. The line 117 indicates the first course of loops of the welt W in an open state.

Prior to knitting the first course of loops 117 of the welt W, the control chains are operated a distance corresponding to a distance relative to

the blank, from the line 115 to the line 117, the machine operating to reposition its various mechanisms.

The stocking leg blank is knit through a course d, see Fig. 9, where a low link 64a of the control chain 64 lowers the lock lever 90, see Figs. 11, 11a, and 11b. During the laying of a course e, a low link 60a of control chain 60 lowers the lock lever 87, and carrier 4 is moved, from an inoperative position, to a position against the lock lever 90, see Figs. 12, 12a, and 12b. During the laying of course f, the yarn of which is fed to the needles 23, by carrier 4, the control chain 64 operates to raise lock lever 90. At this time, carrier 1 is operatively positioned against the lock lever 87, see Figs. 13, 13a, and 13b. During the laying of course g, the yarn of which is laid by carrier 2, the control chain 60 operates to raise lock lever 87, so that carrier 1 may be employed to lay the yarn of the next course, see Figs. 14, 14a, and 14b.

The above-described sequence of operations is for operatively positioning the carriers of the alternating mechanism, which are employed to knit to a course h, as shown in Figs. 9 and 10.

During the knitting of the course h, the control chains 60, 62, and 63 are operated to lower the lock lever 87 for carrier 1, the lock lever 88 for carriers 4, 6, and 8, on the right side of the machine, and lock lever 89 for carriers 5 and 7, on the left side of the machine, see Figs. 15, 15a, and 15b. Line k indicates, as more clearly shown in Fig. 10, an idle course, during which carrier 3 is moved in to the ravelling course selvedge edge M, against lock lever 87; carriers 4, 6, and 8 being held along the selvedge edge P, by lock lever 88, and carriers 5 and 7 being held along the splicing lines R¹ and R², respectively, by lock lever 89, see Figs. 16, 16a, and 16b. Line m indicates an idle course, during which movement, carrier 3 is prevented from returning to its inoperative position along the edge P, by a splicing stop, not shown. During this idle movement of the machine, the lock lever, for carriers 4, 6, and 8, and the lock lever, for carriers 5 and 7, are raised, see Figs. 17, 17a, and 17b.

Knitting is continued through course n, the carrier 4, moving from edge P to edge R, carriers 6 and 8 moving from edge P to lines P² and P¹, respectively, and carriers 5 and 7 moving from lines R² and R¹, respectively, to edge R, while the lock lever 87 remains in its operative position to hold carrier 3, as illustrated in Figs. 18, 18a, and 18b.

In course p, carriers 4, 6, and 8, and carriers 5 and 7, return to the starting point of course n, and the lock levers for these carriers are lowered, see Figs. 19, 19a, and 19b. During the idle course, indicated at r, the carriers, which are connected to the actuator mechanism, are held inoperative by their respective lock levers. Line s indicates another idle course, during the running of which, carrier 2 is moved from the edge R to line R¹, see Figs. 20, 20a, and 20b. During this movement of the machine, lock levers 87, 88, and 89 are raised to release all carriers in the knitting field. Course t indicates the first ravelling course as laid by the carrier 3, see Figs. 9 and 10.

Knitting is continued to a course w, Figs. 9 and 10, in which carriers 2 and 5, and carrier 7, move from edge R to edge K and line R², respectively, carrier 3 moves from edge N to edge M, and carriers 4 and 8, and carrier 6 move from edge H and line P², respectively, to edge P.

During this course, lock levers for all carriers are lowered, see Figs. 21, 21a, and 21b.

Line *x* indicates an idle movement of the couloring mechanism, from edge P to edge R, in which all the carriers are held. Line *y*, see Figs. 9 and 10, indicates an idle movement of the couloring mechanism in which carrier 3 is moved from edge M to its inoperative position outside of edge P, see Figs. 22, 22a, and 22b. During the course, all lock levers are raised to an inoperative position.

As above set forth, there is a single linkage connection, including the link 54, between the auxiliary pattern unit, embodying the shaft 37 and the sprocket wheels, chains, idler wheels, etc. associated therewith, at one end of the linkage, and the cam shaft 10 and the main pattern device M at the other end of the linkage.

This linkage not only transmits the driving force of the cam shaft to the auxiliary pattern chains, but is directly affected at a position locally associated with the cam shaft, in accordance with the selective operation thereof, by the main pattern chain. Thus, by throwing the follower 49 intermittently into and out of engagement with the cam 40, no part of the linkage to the shaft 37 is under constant operation, but operates only in accordance with the pattern.

Although the invention has been explained as operative in effecting of idle courses during the production of a ravel course structure, it is also adapted to operate in like manner, when reciprocable members are to be held stationary during operation of the machine, and without disengaging the reciprocable members from the friction actuating devices, in accordance with a pattern control mechanism.

Further, the improvements specifically shown and described, by which the above mentioned results are obtained, may be modified in various ways without departing from the invention herein set forth and claimed.

I claim:

1. A flat knitting machine comprising knitting mechanism including a bank of needles, means for feeding yarn to said mechanism including a plurality of yarn carriers for reciprocably traversing the needles, actuating means for said carriers, a pattern device, means for effecting operation of said carriers including a plurality of means each responsive to operation of the pattern device for holding a selective plurality of said carriers against, and releasing them for reciprocative movement by said carrier actuating means, and means providing lost motion connection between said pattern device and said plurality of means.

2. A flat knitting machine comprising knitting mechanism including a bank of needles, means for feeding yarn to said mechanism including a plurality of yarn carriers for reciprocably traversing the needles, actuating means for said carriers, a pattern device, means for effecting operation of said carriers including a plurality of means each for locking a selective plurality of the carriers against, and releasing them for, movement by said actuating means, means responsive to operation of the pattern device for selectively actuating said locking and releasing means, and means providing lost motion connection between said pattern device and said plurality of means.

3. A flat knitting machine comprising knitting mechanism including a bank of needles, means for feeding yarn to said mechanism including a plurality of yarn carriers for reciprocably traversing the needles, drive means for said car-

riers, a pattern device and means for effecting operation of said carriers including a plurality of means each for locking a selective plurality of the carriers against, and releasing them for movement by said drive means, means providing lost motion connection between said pattern device and said plurality of means, actuating mechanism for said locking and releasing means, and means automatically responsive to operation of the pattern device for actuating the locking and releasing means to lock and release the carriers relative to the drive means in predetermined sequence.

4. A flat knitting machine comprising knitting mechanism including a bank of needles, means for feeding yarn to said mechanism including a plurality of yarn carriers for reciprocably traversing the needles, drive means for said carriers, a pattern device and means for effecting operation of said carriers including a plurality of means each responsive to operation of the pattern device for holding a selective plurality of said carriers against, and releasing them for, reciprocative movement by said carrier drive means, and means providing lost motion connection between said pattern device and said plurality of means.

5. In a full-fashioned knitting machine, the combination with a knitting mechanism including needles, actuating means therefor including a cam shaft, means for feeding yarn to the needles including a plurality of longitudinally reciprocable yarn-carrier rods, and a main pattern device, of means for controlling operation of the yarn-carrier rods including a plurality of elements each movable for selective locking and releasing relation to a selective plurality of the rods, a plurality of auxiliary pattern devices including one for actuating each of said lock elements, means for connecting the auxiliary pattern devices to, and disconnecting them from, the cam shaft, means operated by the main pattern device for controlling said connecting means, and means providing a lost motion connection between each of said pattern devices and its corresponding lock element.

6. In a full fashioned knitting machine, the combination with a knitting mechanism including needles, actuating means therefor including a cam shaft, means for feeding yarn to the needles including a plurality of longitudinally reciprocable yarn carrier rods, and a main pattern device, of means for controlling operation of the yarn carrier rods including a plurality of elements each movable for selective locking and releasing relation to a selective plurality of the rods, means on the yarn carrier rods for effecting engagement between the rods and the operation-controlling means, a plurality of auxiliary pattern devices including one for actuating each of said lock elements, means for connecting the auxiliary pattern devices to, and disconnecting them from, the cam shaft, means operated by the main pattern device for controlling said connecting means.

7. In a full-fashioned knitting machine, the combination with a knitting mechanism including needles, actuating means therefor including a cam shaft, means for feeding yarn to the needles including a plurality of longitudinally reciprocable yarn-carrier rods, and a main pattern device, of means for controlling operation of the yarn-carrier rods including a cam on the shaft, elements movable for selective locking and releasing relation to the rods, a plurality of auxiliary

pattern devices, means including a follower for connecting the auxiliary pattern devices to the cam, and means operated by the main pattern device for selectively rendering the follower operative and inoperative relative to the cam, and means providing a lost motion connection between each of said pattern devices and its corresponding lock element.

8. In a full-fashioned knitting machine, the combination with a knitting mechanism including a needle bank, actuating means therefor including a cam shaft, means for feeding yarn to the needles including a plurality of longitudinally reciprocable yarn-carrier rods, and a main pattern device, of means for controlling operation of the yarn-carrier rods including lock levers pivotally mounted aside the rods for selective locking and releasing relation thereto, a control shaft, an auxiliary pattern device on the control shaft for each of the lock levers, follower levers provided one for cooperation between each lock lever and its corresponding auxiliary pattern device, a ratchet wheel on the auxiliary shaft, a pawl for the ratchet, means including a cam on the cam shaft, and a follower lever linkage for actuating the pawl, and means operating between the linkage and the main pattern device for controlling the connection between the linkage and the cam.

9. In a full fashioned knitting machine, the combination with a knitting mechanism including a needle bank, actuating means therefor including a cam shaft, means for feeding yarn to the needles including a plurality of longitudinally reciprocable yarn carrier rods, and a main pattern chain, of means for controlling idle course movement of the yarn-carrier rods including lock levers pivotally mounted for selective locking and releasing relation to the rods, a control shaft, a chain-supporting wheel on the control shaft for each of the lock levers, idle wheels provided one for the chain of each of the chain-supporting wheels, an auxiliary pattern chain for each of the supporting wheels and its corresponding idler wheel, follower levers provided one for cooperation between each auxiliary chain and one of the lock levers, a ratchet wheel on the auxiliary shaft, a pawl for the ratchet, means including a cam on the cam shaft and a follower lever linkage for actuating the pawl, and means operating between the linkage and the main pattern chain for controlling connection of the linkage to, and its release from, the cam.

10. A flat knitting machine comprising knitting mechanism including a bank of needles, means for feeding yarn to the knitting mechanism including a plurality of yarn-carrier rods for reciprocally traversing the needles, actuating means for the carrier rods, a pattern device, and means for effecting operation of the carrier rods including a plurality of movable lock members extending transversely to the rods responsive to operation of the pattern device for movement in selected sequence and each embodying one or more lock portions of different number and location from the corresponding portion or portions of another of the lock members for cooperation with a selected number of the rods, at least one of the lock members having a space between two lock portions avoiding interference of the member with a rod between the rods cooperating with its lock portions.

11. A flat knitting machine comprising knitting mechanism including a bank of needles, means for feeding yarn to the knitting mecha-

nism including a plurality of yarn-carrier rods for reciprocally traversing the needles, actuating means for the carrier rods, a pattern device, and means for effecting operation of the carrier rods including a plurality of levers pivoted about an axis parallel to the rods responsive to operation of the pattern device for movement in selected sequence and each embodying one or more depending lock portions of different number and location from the corresponding portion or portions of another of the levers for cooperation with a selected number of the rods, at least one of the levers having a space between two lock portions avoiding interference of the lever with a rod between the rods cooperating with its lock portions.

12. A flat knitting machine comprising knitting mechanism including a bank of needles, means for feeding yarn to the knitting mechanism including a plurality of yarn-carrier rods for reciprocally traversing the needles, actuating means for the carrier rods, a pattern device, and means for effecting operation of the carrier rods including a plurality of levers responsive to operation of the pattern device for movement in selected sequence each pivoted about an axis parallel to the rods and embodying one or more lock portions of different number and location from the corresponding portion or portions of another of the levers along an edge transverse to the rods for cooperation with a selected number of the rods, at least one of the levers having a space between two lock portions avoiding interference of the lever with a rod between the rods cooperating with its lock portions.

13. A flat knitting machine comprising knitting mechanism including a bank of needles, means for feeding yarn to the knitting mechanism including a plurality of yarn-carrier rods for reciprocally traversing the needles, actuating means for the carrier rods, an auxiliary pattern device, a main pattern device for controlling the auxiliary pattern device, and means for effecting operation of the carrier rods including a plurality of movable lock members extending transversely to the rods each including one or more lock portions of different number and location from the corresponding portion or portions of another of the lock members for cooperation with a selected number of the rods, at least one of the lock members having a space between two lock portions avoiding interference of the member with a rod between the rods cooperating with its lock portions, and follower means actuated by the auxiliary control device for operating the lock members.

14. A flat knitting machine comprising knitting mechanism including a bank of needles, means for feeding yarn to the knitting mechanism including a plurality of yarn-carrier rods for reciprocally traversing the needles, actuating means for the carrier rods, an auxiliary pattern device, a main pattern device for controlling the auxiliary pattern device, a narrowing carriage, and means for effecting operation of the carrier rods including a plurality of movable lock members on the narrowing carriage each including one or more lock portions of different number and location from the corresponding lock portion or portions of another of the lock members for cooperation with a selected number of the rods, follower means fixed longitudinally of the carrier rods and actuated by the auxiliary control device for operating the lock members, and means for compensating for movement of the lock members by the

narrowing carriage relative to the follower means including an extensible connector between the follower means and the lock members.

- 5 15. A flat knitting machine comprising knitting mechanism including a bank of needles, means for feeding yarn to the knitting mechanism including a plurality of yarn-carrier rods for reciprocally traversing the needles, actuating means for the carrier rods, an auxiliary pattern device, 10 a main pattern device for controlling the auxiliary pattern device, and means for effecting operation of the carrier rods including a plurality of levers pivoted about axes parallel to the rods and each embodying one or more portions of different number and location from the corresponding portion or portions of another of the levers along an edge transversely of the rods for cooperation with a selected number of the rods, at least one of the levers having a space 15 between two lock portions avoiding interference of the lever with a rod between the rods cooperating with its lock portions, and follower means actuating by the auxiliary control device for operating the levers.
- 15 20 25 16. A flat knitting machine comprising knitting mechanism including a bank of needles, means for feeding yarn to the knitting mechanism including a plurality of yarn-carrier rods for reciprocally traversing the needles, actuating means for the carrier rods, an auxiliary pattern device, a main pattern device for controlling the auxiliary pat-

tern device, a narrowing carriage, and means for effecting operation of the carrier rods including a plurality of levers pivoted about axes parallel to the rods and each embodying one or more portions of different number and location from the corresponding portion or portions of another of the levers along an edge transversely of the rods, for cooperation with a selected number of the rods, follower means fixed longitudinally of the carrier rods and actuated by the auxiliary control device for operating the levers, and means for compensating for movement of the levers by the narrowing carriage relative to the follower means including an extensible connector between the follower means and the levers.

10 15 20 25 25 17. In a straight knitting machine, the combination with knitting mechanism including needles, actuating means therefor including a cam shaft, means for feeding yarn to the knitting mechanism including a plurality of reciprocable yarn carriers, and a main pattern device, of means for controlling operation of the yarn carriers including a cam on the shaft, elements movable for selective locking and releasing relation to the carriers, a plurality of auxiliary pattern devices for operating said elements and means operated by the main pattern device for selectively operating the auxiliary pattern devices.
